CLAIM

The ornamental design for a computing device, as shown and described.

DESCRIPTION

FIG. 1 is a perspective view of a computing device showing our new design;

FIG. 2 is a front view of the computing device of FIG. 1; FIG. 3 is a rear view of the computing device of FIG. 1; FIG. 4 is a left side view of the computing device of FIG. 1; FIG. 5 is a right side view of the computing device of FIG. 1;

FIG. 6 is a top view of the computing device of FIG. 1; FIG. 7 is a bottom view of the computing device of FIG. 1; FIG. 8 is a top view of another embodiment of the computing device of FIG. 1; and, FIG. 9 is a perspective view of the computing device of FIG. 8.

Broken lines seen in the drawings depict portions of the computing device that form no part of the claimed design.

1 Claim, 7 Drawing Sheets
